UNITED STATES PATENT OFFICE.

JAY A. FREIDAY, OF EAST ORANGE, NEW JERSEY, ASSIGNOR TO THOMAS E. MURRAY,
OF BROOKLYN, NEW YORK.

BOILER CONSTRUCTION.

Application filed May 27, 1924. Serial No. 716,126.

My invention aims to provide certain improvements in boilers and particularly in boilers having water walls such as have been described in certain recent applications of 5 Thomas E. Murray, of which No. 678,443 will serve as an example.

The accompanying drawings illustrate an embodiment of the invention.

Fig. 1 is a longitudinal section more or less 10 diagrammatic, of a boiler to which my improvement is applied;

Fig. 2 is an elevation of an auxiliary superheater shown separately from the other parts of the boiler;

15 Fig. 3 is a diagram, in elevation, of a tubular water wall and the circulating connections thereof;

Fig. 4 is a detail in cross-section.

Referring to the embodiment of the invention 20 illustrated, the furnace is provided with stoker grates 1 at opposite sides of the furnace chamber indicated as a whole at 2 in which the combustion of the gases takes place. The main boiler tubes 3 extend between headers 4 and 5. Above these are the supplementary boiler tubes 6 extending between headers 7 and 8, and a steam drum 9 with the usual 25 circulating connections. The heating gases pass out by the pipe 10 to the stack.

30 One or more of the walls is provided with an inner water screen or wall made up of tubes 11 with lateral flanges 12 as shown in cross-section in Fig. 4. These tubes communicate at the upper end with a header 13 and at the lower end with a header 14. Above the drum 13 there is a mud drum 15 connected with the 35 headers 4 by tubes 16 constituting a continuation of the water wall. The tubes 11 of the water wall lead through headers 13 and pipes 13^a to the drum 9, whence pipes 14^a return 40 water to the header 14. A very high efficiency is obtained by the use of such a water wall. The pipes thereof may be arranged in various 45 locations and groups according to the design of the furnace and boiler.

Ordinarily superheaters for water tube boilers of the class illustrated comprise small tubes such, for example, as 17 extending across above the water tubes. The steam 50 from the main drum 9 passes by a pipe 18 to the tubes 17, whence it passes to an outlet pipe 19 and thence to the steam engine.

I propose, however, to provide an auxiliary superheater which serves a double purpose, the efficient superheating of the steam and 55 protection of the water wall headers or drums. Such a superheater, for example, comprises a screen of vertical tubes 20 located on the inner side of the drums 13 and 15.

Fig. 2 is a view of this auxiliary superheater from the outer side, omitting the water wall of the boiler. The steam passes by any suitable piping, indicated diagrammatically by the dotted line 21 to a header 22 on the outside of the boiler, thence by small tubes 23 65 passing through the spaces between the tubes 16 to the tubes 20 of the auxiliary superheater; thence by similar cross tubes 24 from the lower ends of the tubes 20 through the spaces between the tubes 11 to a header 25 and out by 70 a pipe 26 to the point of consumption.

The auxiliary superheater is exposed to the radiant heat from the fire bed and therefore, like the water wall, is most highly efficient in transmitting heat to the steam within the 75 tubes. Thus a very small quantity of piping in the auxiliary superheater may be substituted for a considerable quantity of piping taken away from the usual or main superheater located above the tubes 3 and heated 80 only by convection by the gases which have passed around the tubes 3. The auxiliary heater forms also a shield partly covering the drums 13 and 15. It may in fact be arranged to shield in whole or in part any pipes which 85 would otherwise be exposed to the direct radiant heat of the fire. The mud drum 14 at the bottom of the water wall is protected from the radiant heat by a metal shield 27 which is exposed to the air on the outside so as to itself 90 be protected from overheating.

Though I have described with great particularity of detail a certain embodiment of my invention, yet it is not to be understood therefrom that the invention is restricted to 95 the particular embodiment disclosed. Various modifications may be made by those skilled in the art without departure from the invention as defined in the following claims.

What I claim is:

1. The combination with a boiler having a mud drum 15 of a furnace having a tubular water wall with a top header 13 and a shield 100 on the inner side of said mud drum and top

header comprising tubes 20 extending over the inner sides thereof.

2. The combination with a water tube boiler of a furnace having a wall of vertical water tubes and a horizontal header for said tubes within the outer shell of the furnace, a shield of vertical fluid-carrying tubes over the inner

side of said header, a header outside the furnace and transverse tubes passing between said water tubes and connecting the outside 10 header to the tubes of said shield.

In witness whereof, I have hereunto signed my name:

JAY A. FREIDAY.
